UNITED STATES PATENT OFFICE

CHARLES DOERING, OF CHICAGO, ILLINOIS

LIQUID MERCHANDISE DISPENSER

Application filed December 10, 1928. Serial No. 324,966.

This invention relates to merchandising devices and more particularly to refrigerated liquid venders, although certain features thereof may be employed with equal advantage for other purposes.

5 It contemplates more especially the provision of a simple and improved merchandising device for dispensing liquids to the trade in a refrigerated or cool state.

10 Numerous types of liquid dispensers have heretofore been proposed, but these are not suitable or entirely satisfactory for out-of-door vending at beaches and other places of amusement. It is necessary or at least highly desirable that liquids such as orange juice, buttermilk and kindred drinks be dispensed in a cool state in order to render such saleable as a refreshing drink.

Moreover, outdoor or temporary dispensing stations are devoid of the usual waste accommodations, and therefore ordinary liquid vendors are not suitable for such situations. To this end it is highly desirable to provide convenient drainage for the refrigerated chamber together with such other expedients which not only are conducive to more convenient operation, but also enable dispensing of fluids to the trade with minimum labor and maximum sanitation.

25 One object of the present invention is to simplify the construction and improve the operation of devices of the character mentioned.

Another object is the provision of an efficient and novel refrigerated chamber in communication with liquid vending means to maintain the liquid at a refreshing temperature during summer heat for selective dispensing.

30 A further object is the provision of novel means for draining the refrigerator chamber of a dispensing device with utmost cleanliness and minimum labor.

Still a further object is the provision of novel refuse confining means in association with a dispensing device to facilitate out-of-door liquid vending with minimum inconvenience and labor.

35 Still a further object is the provision of novel means for retaining auxiliaries in as-

sociation with a vending device to enable the more convenient dispensing of liquids therefrom for consumption on beaches or other places of amusement where the usual accommodations are not available.

40 Other objects and advantages will appear from the following description of an illustrative embodiment of the present invention.

In the drawings:

45 Figure 1 is a sectional view in elevation of a device embodying features of the present invention.

Figure 2 is a fragmentary rear view of the device disclosed in Figure 1.

50 Figure 3 is a view in elevation of a container employed in connection with the refrigerator chamber shown in Figure 1.

Figure 4 is a plan view of the container disclosed in Figure 1.

55 Figure 5 is a front view in elevation of a device disclosed in Figure 1.

Figure 6 is a fragmentary sectional view of the superstructure sustainable by the stand disclosed in Figure 2.

60 Figure 7 is a view in elevation of a liquid confining container adapted for reception in the member disclosed in Figure 3.

Figure 8 is a fragmentary view in elevation of a means for shading the device disclosed in Figure 1.

65 The structure selected for illustration comprises a tubular base 10 preferably though not essentially of semi-spherical configuration. The base 10 merges in a cylindrical

70 standard 11 disposed vertically to sustain a casing 12 thereon which in this instance is of spherical configuration in order to harmonize with the specially contoured base 10 to impart an ornamental appearance thereto. In

75 order to enable the confinement of liquids within the casing 12, a well 13 is formed therein in any suitable manner, preferably by the disposition of a cylindrical container

80 14 serving to define the outlines thereof. Heat transmission and conduction between the casing 12 and the well 13 may be reduced

85 to a minimum by filling the space therebetween with cork 15 or other insulating ma-

55

terial which thermally shields the container 14 on all sides thereof.

The well 13 is open at the top thereof to receive an open mouthed container 16 of smaller diameter than the well 13 to define a circumferential compartment or chamber 17 therebetween. To maintain the container 16 in concentric spaced relation with the well defining container 14, spacer brackets 18 are provided for that purpose. The brackets 18 have articulated extensions 19 formed thereon for secured to the exterior wall of the container 16 by means of fasteners 20, thereby presenting bent terminals 21 which impinge against the circular wall 14 of the well 13. Any number of spacer brackets 18 may be employed, there being shown in this instance four which are deemed sufficient to concentrically space the container 16. The container 16 is preferably provided with apertures 22 over the entire periphery thereof to permit circulation and ventilation from the chamber 13 which is filled with any suitable refrigerant such as ice. The liquid confining container 23 of somewhat smaller dimensions than the refrigerant defining container 16 disposed therein to receive any desired liquid such as orange juice, butter milk or kindred refreshing drinks for dispensation in a manner described more fully hereinafter.

As shown, the container 23 has beaded periphery 24 which serves as a reinforcement therefor as well as enables the more convenient removal thereof from the perforated container 16, the former projecting therefrom to receive a closure 25 thereon. It will be noted that the well 13 and the closure 25 telescopically receive a horizontally disposed circular drip plate 26 therebetween. The plate 26 terminates in an upwardly directed peripheral flange 27 to retain any waste liquids which may be accidentally deposited thereon while a downwardly projecting flange 28 is received within the well 13 to effect the support thereof. The closure 25 has a depending circular tubular body 29 shaped for telescopic reception in the well 13, it being filled with insulating material such as cork 30 to minimize thermal transmission therethrough.

The closure 25 has a central aperture 31 therein to receive a dispensing mechanism 32 therethrough. The liquid dispensing mechanism 32 is supported by a plate 33 which serves as a closure for the aperture 31, there being a manually operated pump 34 thereon to effect the withdrawal of the liquid within the container 23 through a suitable spout 35 in the customary manner. The refrigerant confined within the chamber 17 must necessarily be drained owing to its gradual change in state from solid to liquid in the event that ice is resorted to for this purpose. To this end the bottom of the cas-

ing 12 is provided with perforations 37 disposed in circular formation for communication with a funnel 38 adhesively or otherwise secured to the bottom exterior of the casing 12 for disposition in the standard 11 of the base 10. The funnel 38 communicates with a transversely disposed tube 39 which projects through the wall of the standard 11 to receive a flexible hose 40 thereon for directing the discharge of the liquid from the refrigerant chamber 17. The perforations 37 may be disposed in the bottom of the well defining container 14 rather than communicate therewith through a passage 37. The bottom of the container 14 may have a central perforation 31 to enable access of the refrigerant to the bottom of the liquid confining chamber 23, these being supported by a diametrically disposed strip 38 associated with the bottom of the container 16.

It has been found desirable to provide a refuse receptacle 41 to receive paper receptacles and other utensils employed in connection with the liquid dispenser. As shown, the refuse receptacle 41 is formed on the casing 12 and base 10 between the neck 11 thereof, it comprising a metallic body preferably with an inclined wall 42 which projects from the peripheral edge of the base 10 to a point approximate to the horizontal median line of the casing 12. The body 41 terminates upwardly in an orifice 43 provided to enable access to the interior thereof and the hose 40. A suitable closure 44 is hinged to cooperate with the orifice 43 of the receptacle 41 to normally prevent free access thereto.

A compartment 45 is formed in the receptacle 41 near the mouth 43 thereof to accommodate wiping cloths or other expedients such as sponges used in cleansing the stand or any portion thereof. The closure 44 serves to simultaneously prevent access to the interior of the receptacle 41 and its smaller cloth receiving compartment 45. The lower portion of the receptacle 41 is provided with a removable closure 47 which is hinged or otherwise associated therewith to enable the projection of the hose 40 therethrough in order to drain the contents of the refrigerant chamber 17. Otherwise drainage is prevented by merely projecting the hose 40 upwardly against the wall of the compartment 45, thereby conveniently controlling the discharge of the waste liquid from the refrigerant chamber 17.

The casing 12 is provided with a super structure of any desired type which may serve as an advertising or shade medium for the casing 12 and the attendant. To this end the drip plate 26 is provided with parallel spaced vertical standards 48 which comprise tubular sections 49, 50 and 51 having the lowermost one 51 rigidly secured to the drip plate 26 in any suitable manner. The section 50 has

a bracket 52 integrally or otherwise formed thereon to receive a paper cup dispenser mechanism 53 having a paper cup confining container 54 in telescopic association therewith. These sections are maintained in position by means of rods 55 which project therethrough to carry any suitable display medium or ornamental plate 56. The display medium consists, in this instance, of a circular ornamental plate having spaced pairs of aligned sleeves 57 formed thereon for reception by the rods 55. Winged set screws 58 project through the sleeves 57 in threaded engagement therewith to impinge against the rods 55 for holding the placard or ornamental plate 56 at any desired elevation thereon.

Owing to the fact that dispensing devices of this character are employed at the beaches and other open amusement places, it has been found desirable to resort to a sun umbrella 60 having an axial standard 61 which is telescopically received in a T-union 62. The T-union 62 is engaged by horizontally disposed rods 63 having vertically extending tubular sleeves 64 associated with the extremities thereof. Winged set screws 65 project through the sleeve 64 to engage the vertically extending rods 55 in order to effect the support of the sun umbrella 60 which may be employed in connection with or independent from the ornamental display plate 56.

Various changes may be made in the embodiment of the invention herein specifically described without departing from or sacrificing any of the advantages thereof as defined in the appended claims.

I claim:

1. In a device of the character described, the combination with a casing having a well, 40 a perforated shell disposed in said well to define a refrigerant space therewith, spacer means on said container to engage said well, a fluid confining container disposed in said shell, a closure for said well, a dispenser 45 mechanism carried by said closure in communication with the interior of said container, a tubular standard for supporting said casing, a receptacle formed laterally of said casing and standard in integral association therewith, means in said receptacle for draining said refrigerant space, a refuse receiving compartment in said receptacle, a hinged closure for said receptacle and waste receiving compartment, and another closure 50 at the base of said receptacle to remove the contents therefrom and enable access for rendering said drain means operative.

2. In a device of the character described, the combination with a standard, of a casing 60 having a well carried by said standard, fluid dispensing means in communication with said well, a refrigerant chamber in said well, a refuse receptacle formed integral with said casing and standard, a drain between said refrigerant chamber and standard, a flexible

hose in said receptacle communicating with said drain for directing the discharge therefrom, a removable closure in said receptacle near the base of said standard to enable access to the refuse and flexing control of said 70 hose, and a pivotal closure near the top of said receptacle to permit the deposition of refuse therein and greater access for positioned flexing of said hose.
